REVOLVABLE DISPLAY RACK

William Woodburn, Jersey City, N.J., assignor to Glamorene Products Corporation of Delaware, a corporation of Delaware

Filed May 3, 1966, Ser. No. 2,137

Term of patent 14 years

(Cl. D80—10)

FIGURE 1 is a perspective view of a revolvable display rack showing my new design, the fragmentary broken line showing of a display stand being for purposes of illustration only;

I claim:

The ornamental design for a revolvable display rack, substantially as shown and described.
